RALPH L. PARSHALL, OF FORT COLLINS, COLORADO, DEDICATED BY ASSIGNMENT TO
THE GOVERNMENT AND PEOPLE OF THE UNITED STATES OF AMERICA

VORTEX SAND TRAP AND DEFLECTOR RIFFLE

Application filed September 14, 1931. Serial No. 562,739.

(GRANTED UNDER THE ACT OF MARCH 3, 1883, AS AMENDED APRIL 30, 1928; 370 O. G. 757)

This application is made under the act of March 3, 1883, as amended by the act of April 30, 1928, and the invention herein described, if patented, may be manufactured and used by or for the Government for governmental purposes without the payment to me of any royalty thereon.

I hereby dedicate the invention herein described to the free use of the public to take effect upon the granting of a patent to me.

This invention relates to a trap and riffle to free the flow in a canal or other channel wholly or partly of sand, débris and similar material, and has for its object the prevention or reduction in amount of injury resulting from use of water containing considerable quantities of gritty solid matter.

In the accompanying drawings Figure 1 is a plan view of the trap and riffle; Figure 2 is an end elevation of the device, looking upstream; Figure 3 is a vertical section along line 3—3 in Figure 1; Figure 4 is a vertical section along line 4—4 in Figure 1; Figure 5 is a vertical section along line 5—5 in Figure 1; and Figure 6 is a side elevation of one of the riffle plates.

Similar numbers refer to similar parts throughout the several views.

The walls (1) and (2) and the floor (3) form a rigid channel for the stream from which the sand or débris is removed, while the walls (2) and (4) and the floor (5) here represent a subsidiary channel, conduit, or chamber into which the sand or other solid material is discharged by the action of the trap and the riffle. The floor (3) is level in the direction of the flow of the stream, except that the downstream portion is somewhat depressed (see Figures 3 and 5), but may have a slight slope transversely toward the subsidiary or sand outlet channel. The floor (5) has such longitudinal and transverse slopes as may be effective in carrying away the débris and water discharged into the subsidiary channel.

The vortex sand trap consists of a tube (6) laid diagonally across the bottom of the channel essentially as illustrated in Figure 1, the angle (7) ordinarily being between 40 and 60 degrees. This tube is tapered, being some-

what smaller at its upper end than at the end discharging into the sand outlet channel. The tube may have a metal lining as shown in Figure 5, for convenience in construction or for protection against abrasion of the inner surface of the tube. The downstream upper one-quarter of this tube is open (see Figures 3 and 5), with the top of this opening forming a straight edge called the lip (8) coincident with the floor of the upper part of the channel and the lower edge (9) of the opening even with the floor downstream from the tube (6). The larger end of the tube extends through the wall (2) into the sand outlet channel, but the side opening which forms the lip (8) of the trap does not extend through the wall. On the end of the tube (6), in the sand outlet channel, is a double elbow (10) arranged to prevent air from being admitted to the tube. A regulating gate (11) is provided to control the discharge from the tube (6). Triangular baffles (12) and (13) of proper height, shape, and inclination to increase the efficiency of the device are attached to the floor (3) or the lining of tube (6), by suitable means not shown, downstream from and in sufficient proximity to the lip (8).

The deflector riffle is a system of triangular plates (14) fastened to the floor (3) by suitable means not shown, upstream from the vortex tube (6). These plates are of such size, shape and placement as to move the bed load of débris in the stream laterally across the channel to openings (15) through the wall (2) into the sand outlet channel. The riffle has been found most effective when the plates (14) are placed approximately parallel to the vortex tube (6), are graduated in height, and have the downstream angle (16) somewhat greater than 90 degrees. The floor (3) ordinarily is given a lateral slope, as previously stated herein, to increase the effectiveness of the riffle in moving the débris to the side openings (15). These openings are provided with regulating gates (17) to control the rate of discharge through them.

The action of the vortex tube in removing sand and sediment is due to the velocity of the flow in the channel (1—2). The veloc-

ity over the lip (8) creates a negative pressure just under the lip. This negative pressure, aided by the downward component of the current across the opening (8-9) of the 5 tube, causes the whole mass of water in the tube to rotate as indicated by the arrow (18) in Figure 5. The velocity of the flow in the channel also imparts to the water in the vortex tube (6) a movement longitudinally of 10 that tube toward the subsidiary channel. The resulting spiral motion in the tube catches and discharges through the double elbow (10) practically all the sediment and débris carried along in the lower portion of 15 the stream channel (1-2).

Having fully disclosed my discovery, I claim as my invention:

1. A vortex trap and deflector riffle for removing sand and débris from streams comprising a rigid channel having side walls and 20 a floor, a subsidiary channel adjacent to said rigid channel, a tapered tube having an opening on its downstream upper one-quarter portion, laid diagonally across the bottom of said 25 rigid channel and extending into said subsidiary channel, baffle plates attached to the floor of said rigid channel downstream from the tube and close thereto, means to exclude air from said tube, means to control the discharge 30 from the tube, a series of plates attached to the floor of said rigid channel, upstream from the tube, so positioned and formed as to move the bed load of sand and débris in a stream laterally across the channel, openings having 35 regulating gates in the wall between said rigid channel and subsidiary channel so placed as to catch the sand and débris as they arrive at said wall and conduct them to said subsidiary channel.

40 2. A vortex trap for removing sand and débris from streams comprising a rigid channel having side walls and floor, a subsidiary channel adjacent to said rigid channel, a tapered conical tube having a longitudinal 45 opening on its downstream upper one-quarter portion, laid diagonally across the bottom of said rigid channel and extending into said subsidiary channel, baffle plates attached to the floor of said rigid channel, downstream from said tube and close thereto, means to exclude air from said tube and means to control the discharge from the tube.

50 3. A deflector riffle comprising a rigid channel having side walls and a floor, a series 55 of rows of flat triangular plates attached at their lower edges to the bed of said rigid channel, said plates being spaced diagonally across the channel along the rows and so positioned as to cause sand and débris carried in 60 the lower portion of a stream to move laterally across said channel substantially as described.

RALPH L. PARSHALL.
